The ornamental design for a ball ramp for mounting in game table, as shown and described.

DESCRIPTION

FIG. 1 is a perspective view showing the front, right side and top of the ball ramp for mounting in game table showing my new design;

FIG. 2 is a top view thereof;

FIG. 3 is a right side view thereof;

FIG. 4 is a rear view thereof;

FIG. 5 is a left side view thereof;

FIG. 6 is a bottom view thereof; and,

FIG. 7 is a sectional elevational view thereof, taken along line 7—7 of FIG. 4.

The broken line showing of table and accessories is for illustrative purposes only and forms no part of the claim.
